UNITED STATES PATENT OFFICE.

ARTHUR F. GOLDEN, OF SYLVESTER, GEORGIA.

RAILWAY-RAIL JOINT.

1,108,571.

Specification of Letters Patent. Patented Aug. 25, 1914.

Application filed May 4, 1914. Serial No. 836,249.

To all whom it may concern:

Be it known that I, ARTHUR F. GOLDEN, a citizen of the United States, residing at Sylvester, in the county of Worth and State 5 of Georgia, have invented certain new and useful Improvements in Railway - Rail Joints, of which the following is a specification, reference being had to the accompanying drawings.

10 This invention relates to railway rail joints.

The object of the invention is, in a ready and practical manner, to connect the opposing ends of two rails without the employment 15 of fish plates or bolts for the purpose, the assemblage of the parts being such as to render them thoroughly efficient in resisting any tendency to separation or loosening from the vibrations due to the use of the 20 rail, and further so to effect the connection of the rails as to prevent unauthorized persons from loosening the juncture, or of disconnecting the rail sections.

With the above and other objects in view, 25 as will appear as the nature of the invention is better understood, the same consists, generally stated, in a railway rail joint in which the web of one of the juxtaposed rails is provided with an extension having trans- 30 verse notches in its upper and lower edges, and the web of the other rail is formed with a seat to receive the extension, the opposed walls of the seat having spring dogs secured to them and arranged to interlock with the 35 notches, the dogs being so disposed that two keys have to be used simultaneously and turned in opposite directions to throw the dogs out of engagement with the notches.

The invention consists further in the various 40 novel features of construction of a railway rail joint as will be hereinafter fully described and claimed.

In the accompanying drawing forming a part of this specification, and in which like 45 characters of reference designate corresponding parts: Figure 1 is a view in side elevation, partly in section, of a railway rail joint; Fig. 2 is a transverse sectional view taken on line 2—2 of Fig. 1; Fig. 3 is a perspective view of one of the rail sections, and Fig. 4 is a detail view of a key 50 employed in releasing the rail sections.

Referring to the drawing, A and B designate the end sections of two rails, which

may be of the usual or any preferred construction, and therefore need no further description. The rail A is provided with a tapered extension 1, which constitutes a continuation of the web and is provided with upper and lower faces, and at a point 55 intermediate of its ends with longitudinal grooves 2 that intersect transverse notches or seats 3. The rail B is provided in its web with a seat or recess 4 corresponding to the shape of the extension 1, and is provided at 60 its opposite walls with longitudinal grooves 5 in which are secured springs 6, the inner terminals 7 of which are inturned toward each other so as to interlock with the notches 3 in the extension 1 when the two rails are 65 brought closely together. The recess is covered on each side by plates 8 and 9, respectively, which may be riveted on the rail or formed integral therewith, as may be preferred. Where rivets are employed for 70 securing the plates 8 and 9 together, as shown at 13 in Figs. 1, 2 and 3, the heads will be rounded, so that in the event it should be desired to remove the plates for any purpose the heads may be knocked off 75 with a cold chisel. The plates 8 and 9 are each provided with a key hole 10 and 11, respectively, the key hole 10 in the plate 8 being disposed adjacent to the upper walls of the recess 4 and the key hole 11 in the 80 plate 9 adjacent to the lower walls of the recess and in position to permit the ward W of a key K to engage with the inturned end 85 portions of the springs and thus force them down into the recesses 5 and out of engagement with the locking notches 3. It is to be understood that it will be necessary to employ two keys, and the keys must be turned simultaneously and in opposite directions in 90 order to free the locking springs or dogs 95 from the notches 3.

In order to accentuate the connection between the two abutting rail ends, each rail section is provided adjacent to its end with a transverse seat 12 that is designed to receive the cross tie, and thus secure the object sought.

It will be seen from the foregoing description that when once the two ends of the rails are locked together, that it will be impossible for them to become disconnected unless violence is used, without the employment of the keys K, and further that as the locking

springs are housed within the recess 4, they will be protected from the elements, and thus will not be liable to rapid deterioration.

Having thus described my invention, what I claim is:

1. In a railway rail joint, a rail having its web projected to provide an extension provided on opposite sides with notches, a second rail having its web provided with a recess corresponding in contour to the extension and to receive the same, and spring latches carried by the opposite walls of the recess to interlock with the notches in the extension.
- 15 2. In a railway rail joint, a rail having its web projected to provide an extension provided on opposite sides with notches, a second rail having its web provided with a recess corresponding in contour to the extension and to receive the same, spring latches carried by the opposite walls of the recess to interlock with the notches in the extension,

and means for releasing the locking springs whereby to permit separation of the rails.

3. In a railway rail joint, a rail having its web projected to provide an extension provided on opposite sides with notches, a second rail having its web provided with a recess corresponding in shape to the extension and to receive the same, plates covering the sides of the recess, spring locks secured to the opposed walls of the recess and having inturned terminals to engage with the notches in the extension, the plates being provided on opposite sides with key holes disposed adjacent to the locking spring, and keys to engage in the key holes and to release the two springs.

In testimony whereof I hereunto affix my signature in the presence of two witnesses.

ARTHUR F. GOLDEN.
